UNITED STATES PATENT OFFICE.

KARL HUTTER, OF NEW YORK, N. Y.

DESIGN FOR A BOTTLE-STOPPER.

SPECIFICATION forming part of Design No. 25,435, dated April 28, 1896.

Application filed January 13, 1896. Serial No. 575,382. Term of patent 14 years.

To all whom it may concern:

Be it known that I, KARL HUTTER, a citizen of the United States, residing in the city, county, and State of New York, have invented and produced a new and original Design for 5 Bottle-Stoppers, of which the following is a specification.

The leading feature of my design is a plug bottle-stopper of substantially the configuration represented in the accompanying drawing, in which a stopper embodying my design is shown in perspective.

In the drawing, A is the head portion of the plug-stopper. B is the base portion thereof.

C is a bead having its periphery substantially parallel to the periphery of the head portion A.

D is a bead located below and extending beyond the lower edge of the bead C.

What I claim is—

The design for a bottle-stopper, substantially as described herein and shown in the accompanying drawing.

KARL HUTTER.
